UNITED STATES PATENT OFFICE.

EARL ABNER REED, OF OKEMAH, OKLAHOMA, ASSIGNOR TO BESS L. REED, OF HOUSTON, TEXAS.

DEEP-WELL ROTARY DRILLING APPARATUS.

Application filed August 13, 1924. Serial No. 731,782.

This invention is designed to provide a rotary cutter member for deep well rotary boring apparatus in which the cutter teeth are formed in a comparatively thin ring which is mounted removably upon the main body of the cutter so that it may be removed and replaced when worn.

In the accompanying drawings,

Fig. 1 is a sectional view of the cutter.
10 Fig. 2 is a plan view of bearing ring upon which the tooth carrying ring turns and the side members which interlock therewith.

Fig. 3 is an edge view of the bearing ring.
15 Fig. 4 is a face view of one of the members of the main body of the cutter organization.

Fig. 5 is a sectional view of a modification.

In these drawings, 1 indicates a ring or comparatively thin shell having the teeth 2 formed on its periphery. This ring turns on a bearing ring 3 which is held between the members 4 of the main body of the cutter. These members 4 as shown meet on the center line 5 and they have flanges 6 between 25 which the bearing ring is held. The inner ends of members 4 may be spaced apart. The bearing ring is held against rotary movement relative to the main members by tongues or lugs 7 on the latter which enter 30 notches 8 in edges of the bearing ring.

The main members have an opening or bore 9 to receive a pin seated in the walls of the head of the boring bit, between which walls the main body is located. These main 35 members have shoulders 10 to engage complementary shoulders 10^a in the said walls of the bit head to take the up thrust of the cutter when at work on the bottom of the well being drilled. The parts of the cutter 40 are assembled and then slipped into the pocket formed in the drill bit or head to receive it and then the pin is inserted and suitably held in the bit head. The members 4 do not have to be connected together be- 45 cause they will be held in proper position relative to each other by the walls of the pocket in which the cutter is located. Instead of the center pin the cutter organization can be retained in the pocket of the 50 drill bit by other means engaging the sections. The wear ring 3 may be renewed when worn. The tooth carrying ring 1 has a broad rib 1^a which fits between the sides of the members 4 and turns on the wear ring 3. The toothed ring is nearly of the

full width of the main body, it having shoulders overlying the flanges of the body members. In Fig. 5, I show a modification in which the wear ring 3 is omitted, the toothed ring being shown at 1^a and the body mem- 60 bers at 4^a in slightly modified form.

The tooth carrying ring may be of either cylindrical or frusto conical form. The exterior surface of the wear ring 3 may be either cylindrical or frusto conical form to 65 correspond with interior surface of the tooth carrying ring. The interior surface of the wear ring 3 may be cylindrical, square, hexagon, octagon or other form and the surface of the members 4 is made to correspond to 70 the shape of the surface holding these parts against rotary movement relative to each other.

I claim:—

1. In combination in a deep well drilling 75 apparatus, a bit head having a pocket, a rotary cutter organization having a massive body divided into annular sections arranged coaxially, side by side, a comparatively thin ring mounted to rotate on said sections, said 80 ring and body having interengaging thrust sustaining shoulders and centering each other to be handled as one body in placing into or removal from the pocket, said massive body sections bearing on the walls of 85 the pocket and having shoulders engaging complementary shoulders on the walls of the pocket to prevent the body from turning and to sustain the upward thrust, and means engaging the body to hold it within the 90 pocket, substantially as described.

2. In combination with a bit head for deep well rotary drilling having a recess or pocket, a rotary cutter organization to fit said pocket composed of sections divided from 95 each other in a plane transverse to the axis of the cutter, a wear ring and a toothed cutter ring, said wear ring and cutter ring being held by and between said sections, said cutter ring being rotatable on the wear ring, 100 and centering the wear ring and body sections to be handled as one body, substantially as described.

3. In combination with a bit head for deep well rotary drilling having a recess or 105 pocket, a rotary cutter organization to fit said pocket composed of a main body in sections divided from each other in a plane transverse to the axis of the cutter, a wear ring and a toothed cutter ring held by and 110

between said sections, said cutter ring being rotatable on the wear ring, said wear ring having a laterally open notch and the adjacent body section having a projection to enter said notch for holding the ring against rotation, substantially as described.

4. In combination with a bit head for deep well rotary drilling having a recess or pocket, a rotary cutter organization to fit 10 said pocket composed of a main body in sections divided from each other in a plane transverse to the axis of the cutter, a wear ring and a toothed cutter ring held by and between said sections, said cutter ring being 15 rotatable on the wear ring, said wear ring surrounding the sections and interlocking at its edge with the adjacent body section so that upon assembling the parts the wear ring will be held against rotation relative 20 to the section, substantially as described.

5. In combination with a bit head for deep well rotary drilling, having a recess or pocket, a rotary cutter organization to fit 25 said pocket, composed of sections divided from each other, a wear ring and a toothed cutter ring held by and between said sections, said cutter ring being rotatable on the wear ring, said wear ring having means complementary

with the sections for holding the ring against 30 rotation.

6. In combination in a deep well rotary drilling apparatus, a bit head having a pocket, a rotary cutter organization having a massive body divided in a plane transverse 35 to the axis of the cutter into annular sections arranged coaxially, side by side, a toothed cutter ring mounted to rotate on said sections, said cutter ring and body sections having interengaging thrust sustaining shoulders and centering each other to be handled as one body in insertion into or removal from the pocket, said massive body sections bearing on the walls of the pocket, each opposite wall of said pocket having 40 a cutaway portion near its lower end forming a shoulder extending laterally across said wall, said annular sections each having a segmental enlargement providing a chord-like shoulder adapted to cooperate with the 45 complementary shoulders of the walls to prevent the body from turning and to sustain the upward thrust, and means engaging the body to hold it in the pocket.

In testimony whereof, I affix my signature. 50

EARL ABNER REET
